GEARING DEVICE

David Hindahl, Chicago, Ill., assignor to Rodger
Ballast Car Company, Chicago, Ill., a corpora-
tion of Maine

Application June 3, 1940, Serial No. 338,504

6 Claims. (Cl. 74—412)

The invention relates to improvements in a gearing device and has for an object to provide such a device which will be unitary including a housing journaling a plurality of meshing gears and which gears will be suitably journalled by the housing and held against side movement so as to limit end thrusts.

In the drawing the improved gearing device is shown in connection with the operating mechanism of railroad cars, more particularly ballast cars, having hopper doors for discharging lading centrally between the rails of the track. The invention has general utility and the present disclosure is only one of the many applications of the invention, although the same has special utility in connection therewith. The gearing can be readily mounted in operative position in the car, the construction of the same with the input and output shafts is facilitated, and in general, the unitary nature of the present gearing device makes it possible to have the same manufactured separately, simplifying the shop work, and a supply kept on hand, requiring only assembly of the unit with the fabricated car.

Therefore a further object of the invention is to provide an improved construction for supporting and retaining in proper position the gears of the operating mechanism of a ballast car and the like to afford a ready means for mounting these gears in operative position which will dispense with numerous parts and operations.

Another object is to provide a unitary gearing device which can be incorporated as a unit in other structure and which will include a two-part housing member permitting access to or removal of the enclosed gears and having integral bearings providing journaling means for the gears and shoulders for limiting end thrusts.

With these and various other objects in view, the invention may consist of certain novel features of construction and operation as will be more fully described and particularly pointed out in the specification, drawing and claims appended hereto.

In the drawing which illustrates an embodiment of the invention, and wherein like characters are used to designate like parts—

Figure 1 is a cross sectional view taken through the body of a ballast car having hopper doors and comprising one of the many constructions to which the unitary gearing device of the invention may be applied;

Figure 2 is a side elevational view, partly in section, showing the present unitary gearing de-

vice in associated relation with the center sill of the ballast car of Figure 1;

Figure 3 is an elevational view showing the housing member of the gearing device illustrated in Figure 2;

Figure 4 is a sectional view of the housing taken on line 4—4 of Figure 2 with the gears removed;

Figure 5 is a side elevational view, partly in section, illustrating a modified form of unitary gearing device coming within the invention; and

Figure 6 is an end view, part being shown in elevation and part in section, of the device illustrated in Figure 5.

For purposes of illustration the invention has been shown in connection with ballast cars having hopper doors and which requires a shaft extending longitudinally of the car for actuating the doors. The operator, however, rotates a transverse shaft and accordingly it is necessary to provide gearing between the transverse shaft and said longitudinal shaft. The gearing for accomplishing this function can be enclosed in a unitary housing in accordance with the invention, as will be more particularly explained.

Referring to Figure 1, the ballast car 10 has wheels 11 which support by means of the usual trucks and truck bolsters a center sill 12 extending from one end of the car to the other. Extending upwardly from the center sill 12 at each end of the car is an end slope sheet 13 having end flanges suitably riveted to the side walls 14. Extending in a direction inwardly and downwardly are sloping side walls 15, each wall having riveted thereto at intervals an angle member 16 which in turn is secured by the rivets 17 to a cross tie 18. The cross ties strengthen the sloping side walls 15 and centrally thereof they rest on the center sill 12, having a portion cut out at this point to permit passage of the center sill hood 20, which extends over the top surface of the sill from end to end thereof and directs lading to the respective sides.

One or more brackets 21 depend from the center sill, being suitably secured thereto, and which brackets provide supports for the shedding surfaces 22 and journaling means 23 for the longitudinal shaft 24 which for convenience is square in cross section. The crank arms 25 and the links 26 operate the hopper doors 27, mounted for pivotal movement about axes 28. In order that the operator may open and close the hopper doors by rotating the longitudinal shaft 24 a transverse shaft 29 extends from side to side of the car and is operatively connected with shaft

24 by gears, as best shown in Figures 2 and 5. Heretofore various supporting means have been provided for the gears which required several operations in assembling the parts and also complicated the task of removal for inspection or repair. The present invention greatly simplifies this construction and also enables the car builder to incorporate gear mechanism into the car with a minimum of time and labor.

In the modification of Figures 2, 3 and 4 an 10 enclosure is provided in the form of a housing or casting having an upper part 30 and a lower section 31, their meeting edges including outwardly projecting flanges 32, which may be connected together by bolts 33. The laterally extending flange 34 on the upper part 30 enables the casting to be securely fastened as by bolts 35 to the lower flanges of the center sill 12 which locates the upper part well within the center sill and securely holds the gearing device of the invention in assembled relation with the center sill. The longitudinal shaft 24 has engagement with worm wheel 36 which is provided with a squared opening for receiving the shaft, thus uniting the parts in a non-rotating relation. The worm wheel has hub members 37, Figure 3, extending from either side thereof, which hub members extend through openings in the respective sides of the casing and are suitably journaled by semi-circular bearings 38 provided by the lower section 31.

The worm 40, located in the upper part 30 of the casting, has meshing engagement with worm wheel 36 and for journaling the worm said upper part 30 provides integral bearings 41, approximately semi-circular, or in more general terms, arcuate in contour and positioned above the hubs 42. The integral shoulders 43 provided by said upper part 30 engage with the face of its respective hub to thereby limit end movement of the worm. The square shaft 29 is passed through an opening also square in cross section, extending through the worm 40 and by rotation of shaft 29, which comprises the input shaft of the present device, it will be seen that rotation will be imparted to the worm wheel 36 and thus the output shaft 24 at a substantial reduction in speed of rotation with a corresponding increase in power delivered.

It is relatively easy to assemble shaft 24 with its worm wheel 36 since the hubs 37 of said worm wheel extend through openings in the casting and are flush with the side walls of the same. In a somewhat similar manner the integral shoulders 43, provided by the upper part 30, form circular openings 44 in this part of the casting through which shaft 29 is passed for associating the same in non-rotating relation with the worm 40. With the casting in proper position within the center sill it will be observed that the center sill has openings formed in its side wall in alignment with openings 44 and through which the shaft 29 is passed for operatively connecting the shaft with the worm 40 of the gearing device. With the gears in meshing relation the thrust on worm 40 is in an upward direction and on worm wheel 36 in a downward direction. Accordingly, the bearings for the gears respectively are so positioned as to take care of this thrust. Arcuate bearings 41 are disposed above the hubs 42 of the worm 40, whereas, arcuate bearings 38 are below the hubs 37 of the worm wheel. End play of the worm 40 is limited by the shoulders 43 and in a similar manner by the integral shoulders 39 for the worm wheel 36.

In the modification of Figures 5 and 6 the enclosure for the gearing is in the form of a casting or frame member having two parts, although the upper part comprises the major portion of the unit. The said upper frame section 130 has laterally extending flanges 132, enabling the frame to be securely fastened to the lower flanges of the center sill 12, thus locating the upper portion of the frame well within the center sill and holding the same properly positioned with respect thereto. The output shaft 124 has engagement with the worm wheel 136, the same having a square opening for receiving the shaft. In this form of the invention the lower section of the frame comprises a bearing insert 138 suitably held in proper position on the upper frame section 130 by bolts 149. The bearing insert provides a bearing of arcuate contour which is positioned on the upper frame section 130 so as to journal the hubs 137 of said worm wheel. Also in this modification the hubs 137 are additionally confined by an upper bearing 150 provided by the upper frame member 130.

The worm 140 has meshing engagement with worm wheel 136 and as described in connection with Figure 2 the said worm is provided with hubs 142 which have contact with journaling means in the form of bearings 141, the same being located above the hubs 142 for the purpose of taking the thrust from the worm, which will be in an upward direction owing to meshing engagement with the worm wheel 136. End movement of the worm 140 is also limited by the respective side walls of the upper frame which form shoulders 143, each hub 142 extending substantially to its respective side wall and accordingly, end movement of the worm in this direction is prevented.

In this form of the invention, as in Figure 2, the gearing is held in meshing relation by bearings formed integral with the frame member and thus the frame comprises a unit that can be easily applied to the center sill and removed, requiring very few operations. The gears are maintained in proper relation with each other at all times and the assembly of the unit with an input and output shaft merely requires that said shafts be inserted through the openings in the gears respectively. In manufacture of such a unit the worm is first inserted into the upper part of the casting or frame against the bearings 41 or 141 which properly locates the hubs with respect to the openings in this part of the frame. The worm wheel is then associated with the lower section and said lower section applied and secured to the upper part. This forms a unitary structure wherein the gears are held in mesh without dependence on the operating shafts.

The invention is not to be limited to or by details of construction of the particular embodiment thereof illustrated by the drawing, as various other forms of the device will of course be apparent to those skilled in the art without departing from the spirit of the invention or the scope of the claims.

What is claimed is:

1. In a gearing device, in combination, a frame member including at least two sections forming a unitary article when connected, one section having aligned openings in opposite end walls and an approximately semi-circular bearing provided by said section adjacent each end opening and which are concentric with said openings, a worm journaled by said semi-circular bearings, said worm having an axial opening there-

through to receive a shaft extending through the aligned openings for non-rotatably connecting the shaft with the worm, said other section providing approximately semi-circular bearings in opposite side walls thereof and which form aligned openings with the first mentioned section when in connected relation therewith, said last mentioned aligned openings coinciding with the bearings provided by said other section, and a worm wheel journalled by the bearings of said other section and having hub portions extending through said aligned openings.

2. In a gearing device, in combination, a frame member including at least two sections forming a unitary article when connected, one section having aligned openings in opposite end walls and an approximately semi-circular bearing provided by said section adjacent each end opening and which are concentric with the openings, a worm journalled by said semi-circular bearings, said worm having an axial opening therethrough to receive a shaft extending through the aligned openings for non-rotatably connecting the shaft with the worm, said other section providing approximately semi-circular bearings in opposite side walls thereof and which form aligned openings with the first mentioned section when in connected relation therewith, said last mentioned aligned openings coinciding with the bearings provided by said other section, and a worm wheel journalled by the bearings of said other section and having hub portions extending through said aligned openings, the semi-circular bearings of the sections respectively having their concave surfaces directed toward each other.

3. In a gearing device, in combination, a frame member divided horizontally into upper and lower sections forming a unitary article when connected, the upper section having aligned openings in opposite walls thereof, an approximately semi-circular bearing adjacent the top portion of each opening and an end bearing surrounding each opening, a worm journalled by the semi-circular bearings of the upper section and having engagement with the end bearings to limit endwise movement thereof, said lower section having approximately semi-circular bearings in opposite side walls and which form openings with the upper section in substantial alignment with said bearings when the lower section is in connected relation with the upper section, a worm wheel having hub portions in bearing engagement with the semi-circular bearings of the lower section, and shafts passing freely through the aligned openings of said housing in operative engagement with the worm and worm wheel respectively.

4. In a gearing device, a frame member divided horizontally into an upper and lower section forming a unitary article when connected, the upper section having aligned openings in opposite end walls thereof, an approximately semi-circular bearing adjacent the top portion of each

opening and an end bearing surrounding each opening, a worm having hub portions journalled by the semi-circular bearings of the upper section and having engagement with the end bearings to limit endwise movement, said upper section also having aligned semi-circular openings in opposite side walls extending upwardly from the lower edge of the section, the lower section having corresponding semi-circular openings in its side walls extending downwardly from the upper section thereof to form substantially circular openings when the sections are in connected relation, said lower section providing bearings coinciding with the semi-circular openings in said section, and a worm wheel having hub portions in bearing engagement with said bearings of the lower section.

5. In a gearing device, in combination, a frame member including at least two sections forming a unitary article when connected, a plurality of gears retained by said frame member in meshing relation, the upper section of said frame member having aligned openings in opposite end walls and said section also having an inwardly extending portion adjacent each end opening, said inwardly extending portions each providing a downwardly facing arcuate bearing concentrically disposed with respect to the opening adjacent thereto and of a larger diameter than said opening, said other section providing upwardly facing arcuate bearing portions each forming an end opening with respect to the first mentioned section when in connected relation with the lower edge of said first mentioned section, the said end openings thus formed being concentrically disposed with respect to the arcuate bearing portion and said end openings being located in the opposed side walls of the frame member which form substantially right angles with the end walls.

6. In a gearing device, in combination, a frame member including at least two sections forming a unitary article when connected, a plurality of gears retained by said frame member in meshing relation, the upper section of said frame member having aligned openings in opposite end walls and said sections also having an inwardly extending portion adjacent each end opening, said inwardly extending portions each providing a shoulder and having formed integral therewith a downwardly facing arcuate bearing concentrically disposed with respect to the end opening adjacent thereto and of a larger diameter than said opening, and said other section providing upwardly facing arcuate bearing portions each forming an end opening with the first mentioned section when in connected relation with the lower edge of said first mentioned section, the said end openings thus formed being concentrically disposed with respect to the arcuate bearing portions.

DAVID HINDAHL.
